SHOE TREE

William M. Renner, Chicago, Ill., assignor to
Mackie-Lovejoy Manufacturing Company, Chi-
cago, Ill., a corporation of Illinois

Application December 26, 1945, Serial No. 637,232

1 Claim. (Cl. 12—128.1)

1

This invention relates to an improved shoe tree, and in particular, to a shoe tree which is adapted for use with ladies' shoes of the sling strap heel type.

The various types of shoe trees in use are provided with a front member which conforms to the shape of the interior of the toe of the shoe and with a rear member which reacts against the heel portion. When used with a sling strap type of heel, however, the rear member will slip out of engagement with the sling strap.

It is an object of this invention to provide an improved shoe tree, the rear portion of which is notched, so that it may interlock with the sling strap of a woman's shoe.

It is a further object to provide a shoe tree which has no separate rear member for engaging the heel of the shoe, but which comprises only a front toe engaging portion and a spring strip, the rear portion of which spring strip is shaped to engage either the usual heel portion of a shoe, or the sling strap of a shoe.

A still further object is to provide in a shoe tree of the type indicated, a special shape for the heel engaging portion of the spring strip, to the end that the spring strip will not bear directly against the edge of the heel portion.

Still another object is to provide a shoe tree having a novel and improved arrangement of parts, and one providing an improved action, and one which can be made inexpensively, and entirely of metal, and embodying an improved front toe engaging member.

Other objects, features and advantages will become apparent as this description proceeds.

With reference now to the drawings, in which a preferred embodiment of this invention is shown—

Fig. 1 is an elevation of a shoe tree;

Fig. 2 is a bottom view of the shoe tree of Fig. 1;

Fig. 3 is a detailed view of the toe engaging member;

Fig. 4 shows the shoe tree as applied to a shoe of the sling strap heel type;

Fig. 5 is a fragmentary view showing the application of the shoe tree to a shoe having the usual heel construction; and

Fig. 6 is a view similar to Fig. 1, but on a smaller scale, and showing the parts in a changed position.

The shoe tree comprises a front toe engaging member 10, and a resilient strip of spring steel 11. The parts are secured together by rivets 12.

The toe engaging member 10 is preferably

stamped from a suitably shaped blank of sheet steel so that the finished article is provided with a slot 13 which is of appreciable width. The slot extends forwardly and downwardly to a point about a half inch from the front edge of the member 10. The slit 16 which is present, due to the stamping operation, is maintained closed by a small reenforcing strip 14 which may be spot welded to the interior of the toe engaging member, as shown in Fig. 2.

The resilient strip 11 is provided with a substantially straight portion 15, and toward its rear portion is provided with a curved portion 16 which is of comparatively small radius and which is curved through an arc of 90 degrees, or less. Adjacent the curved portion 16 is a straight portion 17 about a half inch long, and beyond the straight portion is a curved heel engaging portion 18.

The portions 16, 17 and 18 provide what could be termed a notched portion. When the shoe tree is applied to a woman's shoe 20, as shown in Fig. 4, the sling strap 19 is engaged by the straight portion 17. The interlocking provided by the notched portion and the sling strap serves to maintain the shoe tree in the desired position.

When the shoe tree is applied to a man's shoe 22, as shown in Fig. 5, the portion 18 engages the interior surface of the heel 21 of the shoe, and the edge 23 of the heel is free from any contact with the resilient strip 11. This clearance is desirable for the reason that the edge of the heel is usually provided with stitching 27. This stitching would be unduly worn and perhaps cut, if it were subjected to repeated contact with the resilient strip 11.

Thus, the notched portion of the resilient strip is of utility, both with heels of the usual type and with heels of the sling strap type.

In Fig. 6 is shown the position assumed by the shoe tree when it has been inserted into a shoe. The straight portion 15 assumes a reverse curve which comprises a positive curve 24, and a negative curve 25. When the shoe tree is in this position, the flexing of the resilient strip, as evidenced by the positive curve 24, exerts a torque on the toe engaging member 10 which serves to urge the toe engaging portion tightly against the interior surface of the shoe. The flexing of the portion 25 of the resilient strip serves to urge the toe engaging member 10 forwardly and the heel engaging portion 18 rearwardly with a greater force than would ordinarily be present if the straight portion 15 were not caused to assume a compound curve.

The slot 13 permits a circulation of air through the toe of the shoe, especially when used in a shoe of the type shown in Fig. 4.

Although only a preferred embodiment of this invention has been shown and described herein, it is evident that various changes and modifications may be made therein without departing from the spirit of the invention as defined by the appended claim.

I claim:

A shoe tree comprising a toe engaging member and a resilient strip of metal secured to said toe engaging member and extending rearwardly therefrom, said resilient strip of metal having four portions, the first portion being substantially straight and extending from said toe portion in a direction substantially parallel to the longitudinal axis thereof, the second portion being curved through an arc of substantially 90 degrees, the fourth portion being curved to form a heel engaging portion, and the third portion serving to connect said second and fourth portions and being offset from and disposed substantially parallel to a line tangent to the curves

of said second and fourth portions to provide a notched portion for alternatively engaging the sling strap of a sling strap heel type of shoe, or for clearing the upper edge of the heel portion of a conventional type shoe, when said heel portion is engaged by said fourth portion, said first portion being sufficiently long with respect to a shoe of average length as to cause the same to assume a reverse curve.
